(57) **CLAIM**

The ornamental design for a collar receiver, as shown and described.

DESCRIPTION

FIG. 1 is a front right top perspective view of a collar receiver.

FIG. 2 is a rear left bottom perspective view thereof.

FIG. 3 is a left view thereof.

FIG. 4 is a right view thereof.

FIG. 5 is a front view thereof.

FIG. 6 is a rear view thereof.

FIG. 7 is a top view thereof.

FIG. 8 is a bottom view thereof; and,

FIG. 9 is a front right top perspective view thereof.

The broken lines illustrate portions of the collar receiver that form no part of the claimed design. FIG. 9 illustrates the collar receiver affixed to a collar which is shown in broken lines. The broken lines of FIG. 9 showing the collar illustrate environmental structure and form no part of the claimed design.
